UNITED STATES PATENT OFFICE.

EDWARD H. SHOLAR AND WALTER W. PACE, OF CHATTANOOGA, TENNESSEE, AS
SIGNERS TO THE VOLUNTEER DISC PLOW CO., OF CHATTANOOGA, TENNESSEE.

DISK PLOW.

941,817.

Specification of Letters Patent. Patented Nov. 30, 1909.

Application filed August 15, 1907. Serial No. 388,673.

To all whom it may concern:

Be it known that we, EDWARD H. SHOLAR and WALTER W. PACE, citizens of the United States, residing at Chattanooga, in the county 5 of Hamilton and State of Tennessee, have invented a new and useful Disk Plow, of which the following is a specification.

The general object of the present invention is to provide a disk plow of extremely 10 simple and inexpensive construction, in which all unnecessary parts are eliminated, and in which the necessary adjustments are effected by mechanism of very simple character and maximum efficiency. Subordinate 15 to these general objects are certain specific objects, the most prominent of which are—

First, to provide a novel disk mounting which will enable the disk to be turned more or less to the land, or in other words, ad- 20 justed as to its horizontal angle to the line of draft, which will also enable the disk to be adjusted toward and from the perpendicular plane, and at the same time either elevated or depressed relative to the beam, 25 according to the character of the soil being worked, and which will also enable the disk to be vertically adjusted without a change of either its horizontal or vertical angle. So far as this feature is concerned, the pres- 30 ent application is a division of the co-pending application, Serial No. 328,645, filed July 31, 1906.

Second to provide novel means for mounting the scraper so that said scraper is readily 35 adjustable to properly coöperate with the disk no matter in what relation the latter is positioned.

Third, to provide means whereby a plurality of beams or beam sections may be secured 40 together to provide a gang plow, the different sections or members being readily interchangeable.

An embodiment of the invention that is at present considered the preferable one is 45 illustrated in the accompanying drawings, wherein:—

Figure 1 is a plan view of the plow. Fig. 2 is a side elevation of the same. Fig. 3 is a sectional view of the disk and its mounting. 50 Fig. 4 is a similar view with the parts adjusted to present the disk in a more nearly perpendicular plane and with said disk slightly elevated. Fig. 5 is also a sectional view showing the parts adjusted to likewise

present the disk in a more nearly perpendicular position to slightly depress it. Fig. 55 6 is a modified form of disk mounting simplified, but having somewhat less range of adjustment. Fig. 7 is a view of another modification, showing a still simpler disk 60 mounting. Figs. 8, 9, 10 and 11 are still further modifications of the mounting for the disk. Fig. 12 is a detail sectional view showing the adjustable mounting for the 65 scraper, said mounting being illustrated in elevation. Fig. 13 is a sectional view there- through. Fig. 14 is a detail sectional view on the line 14—14 of Fig. 13. Fig. 15 is a horizontal sectional view through the coupling between the beam members, or sec- 70 tions. Fig. 16 is a bottom plan view of the same.

Similar reference numerals designate cor- 75 responding parts in all the figures of the drawings.

In the embodiment illustrated, the frame of the plow consists of beam members or sections 17 having front and rear end por- 80 tions 18 and 19 disposed in obtuse angular relation to their middle portions. The front 80 end portions 18 are preferably disposed in alinement, as illustrated in Fig. 1, and the beam sections or members are connected by a coupling 20. As shown particularly in Figs. 1, 15, and 16, this coupling consists 85 of a cap plate 21 having depending flanges 22 and 23, the flanges being located inside the margins of the cap plate and disposed in angular relation. The flange 23 moreover consists of angularly disposed portions, as 90 shown. The flange 22 is disposed alongside the front portion 18 of the rear beam section or member, and is secured thereto by bolts 24 that pass through said flange, and through openings 25 in the beam member. A suffi- 95 cient number of openings is provided to permit the adjustment of said beam member, as will be evident by reference to Fig. 15. The other flange 23 is located alongside the intermediate portion 17 of the front beam, and 100 the adjacent portion of the rear end 19 of said beam, and clamping bolts 26 are passed through the beam and flange. Thus, the beam sections or members are effectively se- 105 cured together, but they may be separated, and single plows formed therefrom, as will be evident. Moreover while two members are illustrated in the present embodiment, it

will be evident that any desired number may be employed.

Secured to the front end 18 of the front beam member or section is a bracket 27 formed with an upright guide 28 and a beveled segment 29. The guide is vertically movable upon a post 30 supported by a front furrow wheel 31 in any suitable manner. Fulcrumed upon the lower portion of the segment 29 is a front frame adjusting lever 32 having an angularly disposed forwardly extending end or arm 33 connected to the post 30 by a link 34. The lever may be swung in an obvious manner to adjust the front end 10 of the frame vertically, and is retained in its adjusted positions by the usual spring latch 35 arranged to engage the segment.

A rear bracket 36 is bolted to and extends beyond the rear end of the rear beam member 17, and is provided at its ends with a vertically disposed bearing sleeve 37 and a seat spring socket 38. The sleeve 37 constitutes a bearing for the vertically disposed journal 39 of a trailing crank axle 40, on which is journaled a rear furrow wheel 41. A latch 42, mounted on the bracket and operated by a conveniently located treadle 43, serves to normally lock the axle against its swinging movement. This mechanism, however, constitutes the subject-matter of the co-pending application, to which reference has already been made, and needs no detailed description. A seat spring 44 has its lower end located in the seat 38, and secured by a bolt 45, and a seat 46 is mounted on the upper end of the spring.

To the central portion of the rear beam member or section is bolted a land wheel bracket 47 in which is journaled the swinging axle 48 of a land wheel 49. This axle is adjusted with respect to the frame by a lever 50 secured to the axle and retained in its adjusted positions by the usual spring latch 51 engaging a toothed segment 52 fixed with respect to the bracket 47.

To the front end of the foremost beam section or member is bolted a draw-bar attaching plate 52^a to which is pivotally connected, as indicated at 53, a draw-bar 54 by means of which the draft animals are hitched to the plow. It is desirable to dispose the draw-bar in various angular positions with respect to the line of draft, and for this purpose, the plate is provided with a series of bolt holes 55 designed to receive a holding bolt 56 extending through the bar 54. Said bar may therefore be swung upon its pivot, and secured in any desired position by the bolt 56.

The disks 57 are mounted on the rear portions of the beam members or sections, and as usual, are provided with spindles 58, which rotate in boxings 59 located at the lower ends of vertically disposed standards 60. Each standard is rotatable in a disk

supporting bracket 61 secured, in a manner to be explained, to the rear portion 18 of each beam. The disk standard is provided with an angular upper end 62 and a threaded extremity 63, the angular portion being 70 designed for the attachment of an arm 64 retained upon the standard by a nut 65 screwed upon the extremity 63 and bearing against a washer 66 interposed between the nut and angular portion. At a point opposite the arm 64, the bracket 61 is provided with a rigid lug 67, and through this lug and arm is passed an adjusting screw 68 equipped with nuts 69 which clamp the arm and lug, and prevent their relative movement, as clearly shown in Fig. 1. By turning the nuts 69 in the proper direction, the arm 64 may be moved toward or from the lug 67, thus rotating the standard 60 for the purpose of adjusting the angular relation of the disk with respect to the line of draft, or in other words, for the purpose of adjusting the disk to take more or less land. It will be noted that this character of adjusting means permits an exceedingly fine 90 adjustment of the disk or a more extended adjustment thereof if desired. Moreover the disk adjusting means also constitutes retaining means for the disk, and it is therefore unnecessary to operate a separate locking device, in order to hold the disk after the adjusting mechanism has been operated to set the disk at the proper angle. In addition to this adjustment of the disk with respect to the line of draft, the mounting also 100 comprehends means whereby the vertical inclination of the disk may be changed and said disk simultaneously raised or lowered, also means for adjusting the disk vertically without any change of its angular disposition either with respect to the grounds or to the line of draft.

In order to attain these ends, the disk supporting bracket 61 comprises three bracket sections or members 61^a, 61^b, and 61^c, normally occupying horizontally alined positions, as illustrated in Fig. 3 and retained in rigid relation with each other and with the beam by bolts 70 passed through slots 71 in the bracket members, and also through the rear portion 19 of the beam. The bolts are retained by nuts 72 screwed thereon and bearing against a rear side of the beam. The slots 71 are of sufficient extent to permit relative adjustment of the bracket members. The opposite sides of the central member 61^b are reversely curved, as shown in Figs. 3 and 4, and engage the reversely curved adjacent faces of the members 61^a and 61^c, it being understood that the disk standard 60 is journaled in the outer bracket member 61^a. The innermost bracket member 61^c is located against the side of the beam, the contacting faces of these elements being disposed vertically. The various faces of the 130

beam and bracket members are horizontally corrugated for the purpose of insuring their rigid engagement.

It is obvious that if it is desired to adjust 5 the disk vertically without changing its angle, it is merely necessary to loosen the bolts 70 and adjust the entire disk supporting bracket as a unit with respect to the beam. If on the contrary, it is desired to 10 shift the disk to a more nearly perpendicular position without depressing the same or with a slight elevation thereof, the desired end may be attained by loosening the bolt and elevating the outer bracket member 61^a 15 with respect to the central member 61^b, as shown in Fig. 4. If it is desired to adjust the disk to a more nearly perpendicular position and to simultaneously depress the disk, for the purpose of deepening the cut, 20 this may be done by adjusting the members 61^a and 61^b as a unit with reference to the innermost member 61^c as disclosed in Fig. 5. It will thus be seen that the peculiar form of 25 the disk mounting not only provides for a wide range of adjustments both as to the horizontal and vertical angles of the disk but that it also provides for exceedingly fine adjustments. The same is obtained by simple and durable mechanism so that the 30 disk may be adjusted with absolute accuracy to whatever position is best adapted to the particular character of the soil being worked.

In Figs. 6-11 inclusive, modified forms 35 of the disk supporting bracket which fall within the scope of the invention are illustrated. For instance, in Fig. 6, the inner bracket is eliminated, and a member 61^x is interposed between the beam and the member 61^a. In this form of the invention, the bracket is adjusted vertically on the beam, and the upper member 61^a is adjusted in the manner shown in Figs. 4 and 5. In Fig. 7, the member 61^a is directly opposed against 45 the modified form of beam 18^x, the modification consisting in providing the beam with a curved face corresponding to the contacting curved face of the bracket member. In Fig. 8, a bracket member 61^x similar to the member 61^a, but modified by reversely curving its inner edge, is opposed to a modified form of beam 18^y having a convexly curved face opposed to the curved face of the member 61^x. In Fig. 9, the bracket member 50 55 61^x is opposed to a member 61^y identical in construction with the member 61^c shown in Fig. 3, but interposed directly between the beam and the member 61. In Fig. 10, the outer bracket section 61^z is modified by inclining its inner face and by interposing 60 between the said member and the beam, a member 61^z having its inner face opposed to the beam and its outer face inclined in correspondence with the inner face of the member 61^z. In Fig. 11, the construction is

the same as that shown in Fig. 3, except that the member 61^c is integral with the beam. These several modified constructions of the disk mounting are capable of substitution, for that shown in Fig. 3, inasmuch as 70 each possesses one or more of the novel characteristics of the construction first described, and which is perhaps the preferable form of mounting.

A scraper blade 73 coöperates with each 75 disk, and in order that said blade will effectively perform its function, regardless of the adjustment of the disk, a mounting for the scraper having a wide range of adjustment is essential. This mounting is preferably 80 constructed as follows. An upstanding bracket 74 has a lower offset end 75 bolted, as shown at 76 in a seat 77 formed on the outermost bracket member 61^a and the upper end of the bracket 74 is provided 85 with an offset horizontally disposed terminal 78. A convexed bearing head 79 is mounted on the horizontal terminal 78, and is provided with depending ribs 80 that embrace the same. A concaved bearing head 90 95 81 fits upon the head 79, and is provided with a longitudinal slot 82. A holding bolt 83, passing through the terminal 78, the head 79, and the slot 82 has a threaded upper end on which a nut 84 is screwed. Consequently when this nut is tightened, it will be evident that the head 82 will be held against movement, and in different positions while the bolt serves to secure all the parts to the bracket 74. The concaved cap or 100 head 81 is provided with an outstanding arm 85 terminating in an upright sleeve 86, and through this sleeve passes an upright stem 87 having the blade 73 secured to its lower end. A set screw 88, threaded through the sleeve, engages the stem, and serves to hold it against movement. This structure as will be evident permits an adjustment 105 of the scraper blade so that it will properly coöperate with the disk when the latter is 110 adjusted to different various positions, as above described.

From the foregoing, it is thought that the construction, operation, and many advantages of the herein described invention will 115 be apparent to those skilled in the art, without further description, and it will be understood that various changes in the size, shape, proportion, and minor details of construction, may be resorted to without departing 120 from the spirit or sacrificing any of the advantages of the invention.

Having thus fully described our invention, what we claim as new, and desire to secure by Letters Patent, is:—

1. In a disk plow, the combination with a supporting bracket having a lug, of a disk carrying standard rotatably mounted on the bracket and having an arm, and an adjusting bolt longitudinally adjustable in the lug, 130

- the arm of the standard being adjustable upon the bolt longitudinally of said bolt.
2. In a disk plow, the combination with a supporting bracket having an upstanding lug, of a disk carrying standard rotatably mounted on the bracket and projecting above the same, an outstanding arm carried by the upper end of the standard and located over the bracket, an adjusting bolt slidable longitudinally through the lug, the arm of the standard being slidable longitudinally upon the bolt, and nuts mounted on the bolt and engaging opposite sides of both the lug and the arm.
3. In a disk plow, the combination with a beam having a portion disposed at an inclination to the line of draft, of a disk supporting bracket formed of independently movable sections mounted on said portion and having its sections relatively adjustable in a direction transverse to said beam to change the vertical inclination of the disk, means for securing the bracket sections against relative movement and in differently adjusted positions, a depending disk standard mounted in the bracket for adjustment around its own axis, said standard being vertically adjustable with the bracket, means for holding the standard in its adjusted position, and a plowing disk carried by the lower end of the standard, the axis of said disk being at right-angles to the axis of the standard.
4. In a disk plow, the combination with a beam having a portion disposed at an inclination to the line of draft, of a disk supporting bracket mounted on said portion and having a swinging adjustment in a direction transversely thereof and in a substantially vertical plane to change the vertical inclination of the disk, means connecting the beam and bracket for securing the said bracket against movement and in different positions, a disk standard rotatably mounted on the bracket and adjustable therewith, a disk carried by the lower end of the standard, and means separate from the bracket securing means and connecting the bracket and standard and located upon the upper side of the bracket for holding the standard against rotary movement and in different positions.
5. A disk plow including a beam having a portion disposed at an inclination to the line of draft, a bracket section having a swinging adjustment transversely of the beam, means for securing the bracket section in adjusted position, a disk carrying standard rotatably mounted on the bracket section and swinging therewith in a substantially vertical plane, said standard having an arm, and a bolt engaging the arm and bracket section and holding the standard in adjusted position.
6. In a disk plow, a disk supporting structure including a rearwardly extending beam, a plowing disk supporting bracket projecting from one side of the beam and comprising a plurality of independent relatively adjustable sections having corresponding vertically curved contacting faces, means for securing the sections against relative movement and in different relative vertical positions, a vertical disk carrying standard rotatably mounted on one of the sections for adjustment around its own axis, means for holding the standard against rotation in any of its adjusted positions, and a plowing disk rotatably mounted on the lower end of said standard, the axis of said disk being at an angle to the axis of the standard.
7. In a disk plow, a disk supporting structure including relatively adjustable inner, outer and intermediate members, the intermediate member having its opposite faces reversely curved and engaging reversely curved faces of the inner and outer members.
8. In a disk plow, a disk supporting structure including a beam and a disk supporting bracket vertically adjustable relative to the beam and comprising inner and outer and intermediate relatively adjustable members, the intermediate member having its opposite faces reversely curved and engaging reversely curved faces of the inner and outer members.
9. In a disk plow, a disk supporting structure including relatively adjustable inner, outer and intermediate members that are adjustable in vertical directions with respect to each other, and a device that engages all the members for securing them against movement and in relatively adjusted relation.
10. In a disk plow, the combination with a beam, of a bracket section located upon one side of the beam, and adjustable in a vertical direction with respect thereto, said beam having an opening and the bracket section having a slot registering with the opening, a bolt passing through the opening and slot for holding the sections against movement and in different adjusted relation, a disk supporting standard rotatably mounted in the section at one side of the slot, and connections between the upper end of the standard and the upper side of the bracket section for holding the standard against rotation and in different positions.
11. In a disk plow, a disk support including a beam, a disk supporting bracket including a plurality of relatively adjustable members provided with coincident slots, and a retaining bolt extended through the beam and through the slots in the bracket members.
12. In a plow, the combination with a beam, of a plowing disk supporting bracket adjustable thereon, a disk having a standard

rotatable on the bracket, and a scraper co-operating with the disk and having a stem adjustably mounted on the bracket separately from the standard.

5 13. In a plow, the combination with a beam, of a bracket adjustably mounted on the beam, means for securing the bracket against movement and in different positions, a plowing disk journaled 70 on the bracket and adjustable therewith, means connecting the standard and bracket for holding said standard against rotary movement, and a scraper for the disk mounted on the bracket separately from the standard and adjustable with said bracket.

15 14. In a plow, the combination with a beam, of a bracket comprising relatively adjustable members, means for securing the bracket members against relative adjustable 75 movement and in different positions on the beam, a plowing disk carrying standard journaled on the bracket and adjustable therewith, means connecting the standard and bracket for holding said standard against rotary movement, a scraper for the disk having an adjustable connection with the bracket at one side of the standard, and means for securing the scraper against movement relative to the bracket and in different 80 positions thereon.

20 15. In a plow, the combination with a beam having a curved face, of a bracket member having a face curved to correspond to the face of the beam and adjustably retained in contact with the same, a disk carried by the bracket member and adjustable therewith, and a scraper mounted on the bracket and coacting with the disk, said scraper being adjustable with said bracket. 85

25 16. In a plow, the combination with a disk support including a beam, a disk supporting bracket comprising a plurality of relatively adjustable members provided with coincident slots, and a retaining bolt extending through the beam and through the 90 slots, of a disk mounted on the bracket, and a scraper co-operating with the disk and mounted on said bracket.

30 17. In a plow, the combination with a disk supporting bracket, of a disk mounted thereon, a scraper supporting bracket secured to the disk supporting bracket, a convexed head mounted on the disk supporting bracket, a concaved head mounted on the convexed 95 head and having a slot, a bolt passing through the slot, the head and the bracket, said heads being relatively rotatable about the bolt, a sleeve carried by the concaved head, a scraper blade coacting with the disk, and a stem secured to the scraper blade and 100 adjustably fastened in the sleeve.

35 18. In a plow, the combination of a plurality of frame sections each composed of a bar having a middle portion and having its 105 extremities bent at opposite inclinations to

form front and rear arms inclined to the line of draft, said sections being located with their rear arms approximately parallel and their front arms disposed in a common line and end to end, a bracket secured to the middle portion of one section and the forwardly-extending arm of the adjacent section to constitute the sole connecting means between the sections and also a brace between the connected parts of the sections, and fastenings for detachably connecting the bracket and sections together, said bracket and forwardly-extending arms of both sections constituting a beam disposed at an angle to the line of draft and from which 110 the rearwardly-extending arms project laterally.

19. In a plow, the combination with front and rear beam members, each having front and rear angularly disposed portions, both 115 disposed at an inclination to the line of draft, and an intermediate portion that is disposed substantially parallel to the line of draft, the front portion of the rear beam member being alined with the front portion 120 of the front member, and means secured to the front portion of the rear member and the intermediate portion of the front member for securing the members together.

20. In a plow, the combination with a plurality of beam members each having portions angularly disposed to each other, of an angularly-faced bracket engaged with the angularly unlike portions of said members for holding the two angularly like portions 125 alined one behind the other and the other portions of the beam members in substantial parallelism, draft means connected to one of the alined portions, and plowing devices mounted on the parallel portions. 130

21. In a plow, the combination with beam members having angularly disposed portions, of a coupling comprising a substantially triangular plate having angularly disposed flanges, means connecting the angularly disposed portions of the beam members to the angularly disposed flanges and maintaining certain portions of such beam members end to end, and plowing devices mounted 135 on the beam members.

22. In a plow, the combination with beam members, of a coupling comprising a substantially triangular plate having angularly disposed connected flanges, bolts connecting the beam members to the angularly disposed 140 flanges, portions of such members so connected being disposed end to end in substantial alinement, and plowing devices mounted on the beam members.

23. In a plow, the combination with beam members having portions disposed in convergent relation, of a plate located over and overlapping the convergent portions of the beam members and having downwardly extending angularly disposed flanges in the 145

rear of their margins, bolts connecting the convergent portions of the beam members to the flanges and securing the front end of one beam in substantial alinement with and 5 wholly in advance of the front portion of another member, and plowing devices mounted on said beam members.

24. In a plow, the combination with beam members, each comprising angularly disposed portions, certain of the portions of 10 one beam member being disposed end to end and in substantial alinement with the corresponding portions of the other, and other 15 of said portions being disposed in substantial parallelism, of a single coupling for the

member comprising a plate having angularly disposed flanges spaced from the marginal edge of the plate, said plate being located between the beam members, bolts connecting the members to the flanges, and plowing devices mounted on the parallel portions of the beams. 20

In testimony, that we claim the foregoing as our own, we have hereto affixed our signatures in the presence of two witnesses.
